Specification for Design.

Patented May 16, 1911.

Application filed February 17, 1911. Serial No. 609,267. Term of patent 14 years.

To all whom it may concern:

Be it known that I, GEORGE H. POWELL, a citizen of the United States, and a resident of Arlington, in the county of Hudson and State of New Jersey, have invented a new and useful original and ornamental Design for a Tool Member, of which the following is a specification, reference being had to the accompanying drawing, forming part thereof.

My new design is shown in the accompanying drawings, in which—

Figure 1 is a side view, Fig. 2 is a plan of the same, Fig. 3 is an inverted plan of Fig. 1, and Fig. 4 is a front view of the same.

I claim:

The ornamental design for a tool member, as shown.

GEORGE H. POWELL.
